UNITED STATES PATENT OFFICE

ALEXANDER ROITZHEIM, OF DUISBURG-RUHRORT, GERMANY.

MUFFLE FOR REDUCTION-FURNACES.

1,086,939.

Specification of Letters Patent.

Patented Feb. 10, 1914.

Application filed April 22, 1913. Serial No. 762,852.

To all whom it may concern:

Be it known that I, ALEXANDER ROITZHEIM, a subject of the King of Prussia, German Emperor, residing at the city of Duisburg-Ruhrort, in the Kingdom of Prussia, German Empire, have invented certain new and useful Improvements in Muffles for Reduction-Furnaces, of which the following is a specification.

10 My invention relates to an arrangement for carrying-off the reduction gases from zinc furnaces with vertical muffles.

The treating of zinc ores in vertical muffles is rendered particularly difficult by the resistance, which the reduction gases meet while passing through the high column of the charge, by which resistance the passage of these gases, namely zinc vapors and carbonic oxid, may under circumstances also be

20 rendered impossible. In consequence of this resistance offered by the charge, the pressure of the gas in the muffle is increased in such a manner, that the zinc vapors will finally penetrate the always somewhat permeable wall of the muffle and mix with the heating gases, or will force the charge out through the flues provided for the escape of the reduction gases. These dangers can be avoided by providing porous walls or perforated tubes, which extend throughout the entire length of the muffle and carry-off the vapors from all levels, whereupon said vapors are conducted by suitable means into receivers, where they are condensed. The

35 arrangements hitherto employed for this purpose will, however, work satisfactory only as long as the holes and perforations through which the gases shall escape, have not been stopped up by the slagged ores.

40 For metallurgical reasons the charge of a zinc furnace is mixed in such a manner, that the slag will not melt, but on the other hand the ore and its bed-rock will very frequently soften at the temperatures employed in zinc

45 furnaces, to such a degree that it assumes a viscid consistency like that of honey. This softened ore will, after a short while, fill up the holes and perforations in the said walls and tubes, so that they will have to be frequently exchanged. The arrangement ac-

50 cording to the present invention, has the object of obviating these difficulties.

In the accompanying drawing such an ar-

rangement is shown in section in Figure 1. Fig. 2 is a horizontal section through the 55 muffle and the furnace, Fig. 3 is a section through a modification of the muffle.

The muffle comprises an outer casing *a*, having an interior chamber or gas passage *b* which is separated from lateral ore-containing chambers *f* by means of walls formed of a plurality of slats or slabs *c*. These slats are preferably made of refractory material and so arranged that their adjacent edges form horizontal apertures through which 65 the reduction gases pass from the lateral ore-containing chambers *f* into the gas chamber *b* from which said gases escape into a receiver *d* where the zinc vapors are condensed.

70 *g* designates the door closing the bottom of the muffle, *h* the furnace in which the muffles are placed.

For keeping the apertures free of slag, which will deposit on the slats from the 75 charge in the muffle, said slats are mounted, as shown in Fig. 1, at different inclines, so that they can be reached and cleaned from above by means of clearing irons.

In the modification shown in Fig. 3 the 80 slats are arranged vertically beneath each other and at such a distance from each other that they leave apertures, which apertures can be readily reached and cleared, in case they should become choked with slag.

85 As soon as it is observed by the action of the furnace that the apertures are commencing to be choked, the charge is removed from the muffle, the door *e* closing the muffle at the top is opened and the apertures are 90 cleared from above by means of a clearing iron. Of course it is also possible to clear out the apertures in the manner described, without interrupting the reducing process in the muffle, if suitable devices are 95 employed which shall prevent the vapors escaping, after the door *e* has been opened.

I claim:

1. A muffle for reduction furnaces, comprising a vertical casing having a gas chamber therein formed of a plurality of horizontally disposed slats, the adjacent edges of which form apertures.

2. A muffle for reduction furnaces, comprising a vertical casing having a gas chamber 100 therein formed of a plurality of hori-

zontally disposed slats, the adjacent edges of which form apertures situated in converging planes.

3. A muffle for reduction furnaces, comprising a vertical casing having a plurality of horizontally disposed slats mounted therein and arranged to form a converging gas passage, and having their adjacent edges spaced apart to form apertures.

10 4. A muffle for reduction furnaces, comprising a vertical casing having a plurality of horizontally disposed slats forming a central gas chamber and lateral ore containing chambers, the adjacent edges of said slats

15 lying in substantially the same horizontal

plane and spaced apart to form apertures for the passage of gas from the ore chamber to the gas chamber.

5. A muffle for reduction furnaces, comprising a vertical casing having a gas chamber therein formed of a plurality of horizontally disposed slats forming apertures and inclined to the vertical axis of the chamber.

In testimony whereof I have affixed my signature in presence of two witnesses.

ALEXANDER ROITZHEIM. [L. s.]
